DISPENSING MEANS

Application filed February 4, 1929. Serial No. 337,459.

This invention relates to a device for feeding, or supplying, fluid substances to pressure apparatus, such as internal combustion heat motors. Such fluids may be effectively supplied for added lubrication, or for removal of carbon deposits, or prevention of the formation of such deposits, or any other purposes.

The object of the invention is to provide an apparatus which can be easily and economically produced, which can be installed without appreciable expenditure of money, time or skill; which is adjustable between comparatively wide limits to furnish much or little of the fluid substance to the apparatus which it serves, and which supplies the said substance most economically and effectively. Other objects will appear as the description proceeds and will be manifest to those skilled in the art; and the invention consists in the novel and effective provision, combination, association and relative arrangement of parts, members and features, all as herein disclosed and claimed.

The invention in one of its forms, here taken as an example for description, includes parts and arrangement and coordination thereof for feeding a carbon-dissolving and lubricating liquid to a multi-cylinder, internal combustion motor.

In the drawings:

Fig. 1 shows an elevation of the device;

Fig. 2 shows an axial, sectional elevation of the device;

Fig. 3 shows the device installed as applied to a multi-cylinder, internal combustion motor, together with a vacuum feed for gasoline, the two devices being connected to the manifold at the same opening by means of a T, the motor being fragmentally indicated.

Referring to the drawings. A is a container, which, in one of its preferred forms is a glass bottle adapted to receive a screw closure B through which latter passes the member J. As shown, this member is a cylindrical shaped metal piece having a flange K near one end, the opposite end being threaded to receive cap N. P. is a resilient packing ring. Tubes C and D which are the inner and outer tubes respectively are both attached

to the member J, being preferably screwed into place as shown. C is a small tube which, as shown in Fig. 2, has its lower end fastened tightly, being preferably screwed into closure member J. D is a larger tube which surrounds and encloses tube C. Tube D is likewise screwed into place at its lower end in closure member J and there is no connection between the lower ends of the two tubes, both being tightly closed off from the container A at the bottom ends. The upper end of inner tube C terminates slightly below the upper end of outer tube D as indicated. Cover cap E, provided with the two perforations F F extending therethrough, as shown, is screwed on the upper end of the outer tube D and does not contact with the inner tube C at all. Clearly, there is a connection between the inner and outer tubes at the top ends through the cover cap E. G are the small ports made at various levels in the wall of the outer tube D and which provide communication between the container in the inside of the tube D and also between container and the upper open end of tube C.

Pipe O is fastened to the outer end of member J by an elongated portion, or nipple which is threaded as shown, and over which a closure cap N is screwed, through which cap pipe O passes, its end adjacent nipple of member J being enlarged, as shown, so that when the closure cap N is screwed tightly over the nipple of member J, it holds the connecting pipe O in place and makes an air-tight seal at the joint. As shown in Fig. 3, the pipe O connects with manifold R through the connecting T.

Considering the different parts and their operations, it is clear that tube C, terminating high in the container, is the sole communication between the container and the outside. A cover-cap E screwed on the upper end of the tube D covers tube C and encloses it entirely in outer tube D, so that tube D intervenes between the manifold pressure and that in the container A. The inside tube C is connected by pipe O, with the engine manifold, as shown. Obviously, the pressure in the manifold (absolute) will be equal

to that in the connecting tube O and also in the inner tube C in the vessel A. Also, the pressure (absolute) inside the vessel A will become the same as that of the manifold because any change in the manifold pressure is communicated to the container A through the tubes O, C and D after a sufficient time has elapsed for the two pressures to become identical by working through the 10 small ports in the passage from the manifold to the container interior. Clearly, there is no communication between the manifold and the container except through the small holes G G in the side of tube D or holes F F in the 15 top cap. The inner tube terminates below the end of the top cover-cap, so that the pressure existing in the inner tube C, equal at all times to that in the engine manifold, will be communicated to the inside of the outer tube 20 D, the annular space between outer and inner tubes being also subjected to the pressure in the manifold or other part of the motor to which the inner container tube C may be connected.

25 The pressure in the larger tube D in the container A tends to pass to the container all pressure changes which occur in the manifold, but there is a delayed action in this pressure equalization due to the very small area 30 of the holes in tube D and cover-cap E, which provide communication between the inside of the container and the manifold. If the manifold pressure remains constant over any appreciable length of time, the pressure inside 35 the container becomes identical with that of the manifold, but when the pressure in the manifold changes appreciably, some small time period must elapse before the pressure in the container becomes the same as that in 40 the manifold.

45 The effective area of the uppermost holes in the cover-cap F of the outer tube D, is adjustable. By screwing the cap F down over the tube end, more or less, the full area of the 50 holes is changed in accordance with the depth of the tube in the cover-cap and the amount of the hole area covered by the end of the tube screwed therein. If tube D be sufficiently screwed into the cover-cap F, the holes 55 in the cap are completely covered by the portion of the tube projecting into the cap, so that there is no opening through the cap to the container interior. This condition leaves the small ports, in the walls of tube D, the 60 only communicating passages from inside the tube to the outside, or between the container and the manifold. In this case, the equalization of pressure between the manifold and the 65 interior of the container A takes a longer 60 time than it does when the upper holes F F, through the cover-cap E, are partly, or fully, opened. So it is clear that the adjustable openings through the cover-cap F serve the purpose of adjusting the time rate at which 65 the equalization of pressure between the

manifold and the interior of the container may take place.

When the container is full of liquid, the upper level of the liquid is well below that of the holes F F in cover-cap E, as shown. However, the ports, drilled through the tube walls, are all submerged and any reduction in pressure in the manifold will cause a flow from container to manifold. This will force some liquid through the ports in the wall of tube 75 D into this tube, which surrounds the inner tube C, and thence up to the level of the upper end of the inner tube C, thence out through it and the connecting tube O to the manifold where the liquid enters in an undivided state, in the general form of a small stream or trickle, and so distributed through the motor and over the working parts to which the working fluid, or combustible mixture has access. If, on the contrary, the pressure in the manifold rises to a value greater than that in the container, the vapors or gases in the manifold will pass to the container through the openings before described and so 80 continue until the pressures are equalized. Hence, the pressure in the container is continually changing in a delayed, or lagging, attempt to follow the pressure changes in the manifold and when the pressure in the manifold diminishes below that of the container, liquid is fed to the manifold. By adjustment of the uppermost holes F F through the cover-cap E, the quantity of liquid fed to the manifold is adjusted for any given change 90 in pressure of the manifold, or rather pressure difference between that in the container and that of the manifold. This result is due to variation by cap adjustment of the total area of communication between container A and inner tube C. Obviously, if the holes 95 F F through the cover-cap E—which are larger than the ports through the wall of the tube—are left open, lowering of the pressure in the manifold will be attended by an almost instantaneous lowering of the pressure in the container A, by reason of the considerable area connecting the container and the manifold, so that practically no liquid will be forced through the small ports through the 100 wall of the tube; while, if the cover-cap holes F F are completely closed, the only possible avenue of pressure equalization is through the ports G G G in the tube side, so that more 105 will be fed to the manifold before the pressures are equalized than when the ports F F are open. Hence, the holes through the cover-cap are for adjustment of the rate of feed of the liquid.

110 The vacuum feed device is shown in order to indicate the ease with which the container of the present invention may be installed. The opening in the manifold to which the vacuum feed device was connected, has a T T placed in it, the vacuum feed reconnected to one branch of the T and the pipe 115 120 125 130

O, from the liquid feed device, connected to the other branch of the T as shown. The container is fastened to any convenient support by means of the surrounding clamp U, to which is attached, or integral with, the projecting portion S, formed and adapted to be screwed to a panel or wall, or bulkhead or other convenient flat surface adjacent the assembled power unit.

As before explained, the diminution of the pressure (absolute) in the manifold R of the engine, will leave the pressure in the container A higher than that of the manifold, so that the pressure equalization can take place only by a flow from the container A through openings F, F and G, G, G to connecting pipe O. This will mean the passage of air or vapor out of the container A through openings F, F, and of liquid through openings G, G, G. The total quantity of liquid transferred from the container to the manifold for a given pressure drop in the manifold, will, of course, depend on the quantity of air or vapor which can escape through the holes F F during the total time required for the pressure equalization to take place. Hence, as before explained, the openings F F regulate, by the degree of their uncovered area, the quantity of liquid fed to the manifold, and it is at these uppermost openings that adjustments of the device are made.

Obviously, as the level of the liquid falls, and the quantity of vapor in the bottle increases, the number of submerged ports G, and the area through which liquid can pass, decrease; while the number of unsubmerged ports G and the area through which vapor can pass, increase, due to the different elevations at which the ports are located. By this arrangement the tendency of the rate of feed of the liquid to increase as the volume of the expansive vapor in the container above the liquid increases, is compensated, and the rate of liquid feed maintained substantially uniform after the liquid level falls below ports F F.

The use of this apparatus is in nowise limited to feeding liquid to the manifolds of internal combustion motors, but these devices may be used for any purpose where it is desired to deliver a liquid or vapor to any apparatus or mechanism by intermittent, recurrent pressure changes which occur in one member of the apparatus and which may be communicated to the container of the device herein described. So that the purpose and uses of the invention may be many and of widely differing kinds. In important aspects the invention comprises a container into which any kind of fluid, or even finely divided solid substances may be introduced, a means connecting the container to any pressure containing part of a machine or device, and means for regulating the flow of ma-

terial in the container to the portion of the device to which the connecting pipe may be attached.

Having described my invention, in connection with illustrative embodiments, forms and arrangements of parts, it will be understood that many variants thereof are possible to those skilled in the art, and my invention, in its broader aspects, is not limited to the particular construction or application herein shown and described, as changes in the sizes, proportions, configurations, arrangements, assemblage, inter-action, juxtaposition and mechanical relations, as well as additions, omissions, substitutions, combinations and alterations of forms, parts, members, features, and in the kind and order of operations and successive steps may be made without departing from the broad spirit of this invention.

I claim:

1. A device of the character described comprising a container, means forming within said container a separate chamber, means providing communication between said container and said chamber at vertically spaced points, and a conduit communicating with an upper end portion of said chamber, said container being adapted to contain a fluent substance and said conduit being adapted for connection with a source of variable pressure.

2. A device of the character described comprising a container, means forming within said container a separate chamber, said chamber being provided at vertically spaced points with apertures providing communication between the container and said chamber, means for varying the effective area of certain of said apertures, and a conduit communicating with an upper end portion of said chamber, said container being adapted to contain a fluent substance and said conduit being adapted for connection with a source of variable pressure.

3. A device of the character described comprising a container, means forming within said container a separate chamber, a closure for the top of said chamber provided with an aperture affording communication between said container and said chamber, said closure being adjustable to vary the effective area of said aperture, means providing communication between said container and a lower portion of said chamber, and a conduit communicating with an upper end portion of said chamber, said container being adapted to contain a fluent substance and said conduit being adapted for connection with a source of variable pressure.

4. A device of the character described comprising a container, a tube extending upwardly from the bottom of said container and provided at vertically spaced points with apertures, and a conduit terminating within and adjacent to the upper end of said tube.

said container being adapted to contain a fluent substance and said conduit being adapted for connection with a source of variable pressure.

5. A device of the character described comprising a container, a tube extending upwardly from the bottom of said container and in communication with the latter near its lower and upper ends, and a conduit terminating within and adjacent to the upper end of said tube, said container being adapted to contain a fluent substance and said conduit being adapted for connection with a source of variable pressure.

6. A device of the character described comprising a container, a tube extending upwardly from the bottom of said container and provided at vertically spaced points with apertures affording communication between the interior thereof and said container, means substantially closing the upper end of said tube, and a conduit extending upwardly through said tube and terminating adjacent to the top of said tube, said container being adapted to contain a fluent material and said conduit extending exteriorly of the container and being adapted for connection with a source of variable pressure.

7. A device of the character described comprising a container, a tube extending upwardly from the bottom of said container and provided at vertically spaced points with apertures affording communication between the interior thereof and said container, an apertured closure for the upper end of said tube adjustable with respect to the latter to vary the effective area of the apertures therein, and a conduit extending upwardly through said tube and terminating adjacent to the top of said tube, said container being adapted to contain a fluent material and said conduit extending exteriorly of the container and being adapted for connection with a source of variable pressure.

45 In testimony whereof, I have signed my name to this specification at Los Angeles, California, this 16th day of January, 1929.

PAUL N. ELDERKIN.
